(57) **CLAIM**

The ornamental design for a fluid applicator, as shown and described.

DESCRIPTION

FIG. 1 is a perspective view of a fluid applicator showing my new design;

FIG. 2 is a side elevational view thereof, the design being cylindrically symmetrical; and,

FIG. 3 is a right end view of my new design.

The broken lines showing the tip are for illustrative purposes only and form no part of the claimed design.
